UNITED STATES PATENT OFFICE.

HENRY K. HUPPERT, OF SAN FRANCISCO, CALIFORNIA.

RADIOTUBE.

Application filed December 21, 1925. Serial No. 76,820.

This invention relates to improvements in radio tubes and has particular reference to a tube adapted to be employed in any radio receiving circuit, in which an ordinary tube is employed.

The principal object of this invention is to produce a tube wherein the loss of energy within the tube will be greatly reduced.

Another object is to produce a tube where-
10 in self-oscillation may be eliminated.

An additional object is to produce a tube which will be relatively stable.

Other objects and advantages will be ap-
15 parent during the course of the following
description.

In the accompanying drawings forming
a part of this specification, and in which
like numerals are employed to designate
like parts throughout the same,

20 Figure I is a side elevation of my im-
proved tube,

Figure II is a fragmentary detail view
showing the positioning of the four-ele-
ments within my tube,

25 Figure III is an enlarged detail cross
section taken on the line 3—3 of Figure II,

Figure IV is a schematic diagram show-
ing my four-element tube employed as a
detector,

30 Figure V is a schematic diagram showing
my four-element tube so connected as to
function as a radio and audio frequency
tube, and

Figure VI is a schematic diagram showing
35 my four-element tube in an audio frequency
circuit, operating as a push-pull amplifier.

Vacuum tubes, as now used in radio
reception, have a great many limitations,
some of which are the large loss of energy
40 within the tube and self-oscillation due to
capacity effects between the electrodes and
the limited grid control.

I have, therefore, sought to produce a
new tube having a fourth element therein,
45 which is so situated and so connected as to
be, at all times, of an opposite polarity to
the usual grid and so spaced that the fila-
ment will be interposed between this fourth-
element and the usual grid.

50 In the accompanying drawings, wherein
for the purpose of illustration is shown a
preferred embodiment of my invention,
the numeral 5 designates the vacuum re-
ceptacle having a base 6 and the usual con-
necting prongs 7. Within this vacuum re-

ceptacle is positioned a support 8 having
the elements supported thereon.

At 9 I have shown the customary plate
which may consist of two halves as shown
in Figure III, crimped together or may be 60
the tubular form commonly found in the
smaller tubes.

At 11, I have shown the ordinary grid
which is mounted upon the support 8,
while at 12 I have shown the customary 65
filament also mounted upon the support 8
and at 14 I have shown a fourth element tak-
ing the form of a triangular plate. This
fourth element has its major portion parallel
to the plate 9, as will be seen by viewing 70
Figure III.

By again viewing Figure I, it will be
noted that a fifth prong 10 is positioned in
the base, which prong is electrically con-
nected to the fourth element 14.

75 In Figure IV, I have shown a tube hav-
ing a fourth element, which fourth element
is connected to one side of the energizing
coil 16 by a wire 18 the opposite end of
which coil is connected to the grid 11 of 80
the tube by a wire 17. It is, of course,
understood that this coil may be energized
in any suitable manner. The "A" battery
is connected to the filament 12 by wires 21
and 22. The result of this construction is
85 that the tube operates over the entire cycle
in counter-distinction to the operation of a
three-element tube, which operates only on
one-half of the impressed cycle.

In the four-element tube when the grid 90
is charged with a negative potential, the
fourth element will then be charged posi-
tively and from the same source of energy,
with a result that when a negative charge
is placed upon the grid which is interposed
95 between the filament and the plate there will
be no electron flow from the filament to the
plate, due to the negative charge upon the
grid.

100 Should any electrons leave the filament
which is the case in noisy tubes, then the
electrons will be attracted to the fourth ele-
ment which has a positive charge on it,
with the reverse impulse the grid becoming
positive and the fourth element negative,
105 the electrons are permitted to flow from the
filament to the plate. This action is acceler-
ated due to the negative charge of the fourth
element, which being of the same polarity
as the electrons, repels them and hurries 110

them on their way toward the plate. This action gives them greater control or amplification factor than is possible with the three-element tube.

5 Figure V schematically illustrates a fourth-element tube so connected as to function both as a radio and audio frequency tube. The fourth-element being connected to the plate circuit couples the audio frequency back to the radio frequency, thus giving greater amplification.

It will be readily observed that the capacity effect between the grid and the plate is now minimized as the same is in series 15 with the fourth element, thus creating greater radio frequency efficiency and at the same time stabilizing oscillation.

20 In Figure VI, I have shown the tube connected in such a manner that it will function as a push-pull amplifier and by connecting the fourth-element to one end of the transformer coil, the other end of the coil to the grid and one side of the filament

to the middle point of the transformer, the tube will function as a push-pull amplifier, 25 as herein illustrated.

It is to be understood that the form of my invention herewith shown and described is to be taken as a preferred example of the same, and that various changes in the 30 shape, size and arrangement of parts may be resorted to without departing from the spirit of the invention or the scope of the subjoined claim.

Having thus described my invention, I 35 claim:—

In a radio tube having an evacuated chamber, a plate element positioned in said chamber, a filament element positioned within said chamber, a grid element interposed between said filament and said plate, and a fourth-element positioned within said tube 40 in such a manner as to have its margins substantially surrounded by said filament.

In testimony whereof I affix my signature.
HENRY K. HÜPPERT.
